(57) **CLAIM**

The ornamental design for a storage bin, as shown and described.

DESCRIPTION

FIG. 1 is a perspective view of the storage bin;

FIG. 2 is an end elevational view of the storage bin;

FIG. 3 is a side elevational view of the storage bin;

FIG. 4 is a top plan view of the storage bin; and,

FIG. 5 is a bottom plan view of the storage bin.

The broken lines designating the mesh of the storage bin are for illustrative purposes only, they are not intended to designate any particular pattern in the mesh of the storage bin, and they form no part of the claimed design.
